UNITED STATES PATENT OFFICE.

HARRY A. FOOTHORAP, OF HARRISBURG, PENNSYLVANIA, ASSIGNOR TO ELLIOTT-FISHER COMPANY, A CORPORATION OF DELAWARE.

SHIFTING TYPE HEAD.

Application filed April 30, 1923. Serial No. 635,675.

To all whom it may concern:

Be it known that HARRY A. FOOTHORAP, a citizen of the United States, residing at Harrisburg, in the county of Dauphin and 5 State of Pennsylvania, has invented certain new and useful Improvements in Shifting Type Heads, of which the following is a specification, reference being had therein to the accompanying drawing.

10 This invention relates to a shifting type head for typewriters of that class in which a type carrying head mounted on the type bar is automatically shifted to present different type, as for instance upper and lower 15 case type, alternately in the printing position.

The object of the invention is to produce a simple, inexpensive and efficient construction for movably mounting the head on the bar, 20 for shifting the head to upper and lower case position and for securely retaining the head in the selected position.

The preferred embodiment of the invention is shown in the accompanying drawings 25 in which Fig. 1 is a skeleton view of a flat platen typewriter equipped with printing mechanism constructed in accordance with my invention.

Figure 2 is a side elevation of the upper 30 end of the type bar, the shiftable type head and parts associated therewith, one position of the head being indicated in dotted lines.

Figure 3 is a section of the subject-matter of Figure 2.

35 Figure 4 is a detailed perspective view of a group including the type head and the upper end of the type bar or arm.

In the drawings, 1 indicates the type ring of an Elliott-Fisher billing machine supported below a horizontal deck 2 which 40 constitutes the bottom of a carriage 3 movable for letter spacing on a line space frame 4 which advances for line spacing over a stationary flat platen, the printing surface 5 of which is indicated in Fig. 1.

In the type ring 1 is mounted as usual, a series of up-standing type bars 6 at the upper 45 end of each of which is mounted a pivoted type head carrying upper and lower case types 8 and 9 movable alternately into printing position by the shifting of the head 7.

The type bars 6 are moved down to the platen to print by keys 10 connected to the type bars through intermediate connections 55 11 as shown, and said bars are retracted by

retracting springs 12. The bar 6 is formed with a circular upper end 13 substantially conforming in contour to the hub 14 of the head 7 which is reduced in thickness so as to allow the end 13 of the bar to lie within 60 the side plane of the type head.

At the side of the hub 14 opposite the head proper 7, a bifurcated guide and stop 15 is formed integral with the hub and is substantially the same thickness as the head 7. 65 The head 7 and the member 15 are formed with angularly related stops 16 and 17 disposed to engage the front and rear edges of the bar 6 to limit the movement of the head 7 on its axis. This axis in the present instance is in the form of a pivot screw 18 having a head 19 imposed against the hub 14 and the nut 20 screwed on the opposite end of the screw and imposed against the circular 70 end of the type bar.

Pivoted to the head 7 in a plane above and in advance of the axis thereof, in the normal position of the head, as indicated at 21^a is an approximately semi-circular link 21, the lower end of which is located in rear of the type bar at a point below the head 7 and is attached to one end of a head retaining spring 22 extended along the bar 6 and attached at its lower end thereto as indicated 75 at 23. The link is received within the bifurcated guide 15 and is provided with an up-standing trigger 24 which when intercepted during the printing stroke by a trip 25 will cause the head 7 to be shifted from lower 80 case to upper case position. Similarly, upon the retraction of the type bar the trigger 24 will be intercepted by a buffer ring 26 which will cause the retraction of the head 7 to 85 normal lower case position as the bar comes to rest.

It will now be observed by reference to Figs. 1 and 2 that the line of tension between the fixed point 23 and the pivoted connection 21^a between the link 21 and the head 7 will be located in advance of the axis of the head in 90 one position and at the opposite side of said axis in the other position of the head. This will naturally result in the secure retention of the head in either position by the spring 22 since in one case the stop 16 will be held firmly against the front of the type bar and in the other case the stop 17 will be held firmly against the rear of the bar.

105 It is thought that from the foregoing the construction contemplated by my invention 110

will be clearly understood, but I reserve the right to effect such variations thereof as may come fairly within the spirit of the invention as defined in the appended claims.

5. What I claim is:

1. The combination with a type bar, of a type head pivoted thereon, a link pivoted to the head and provided with a trigger, and a head retaining spring connected to the link.
10. 2. The combination with a type bar, of a type head pivoted thereon, a link pivoted to the head and provided with a trigger, means for guiding the link, and a head retaining spring connected to the link.
15. 3. The combination with a type bar, of a type head pivoted thereon and provided with printing types and a guide at opposite sides of its axis, a link received by the guide pivoted to the head and having a projecting trigger and a head retaining spring connected to the link.
20. 4. The combination with a type bar, of a hub mounted at the upper end of the bar, a head and a guide extended from opposite sides of the hub and coacting with the bar to limit the movement of the head in opposite directions, a link pivoted to the head
- 25.

and extended through the guide, a head retaining spring connected to the link, and a trigger extended from said link.

5. The combination with a type bar with a type head pivoted thereon, of a head retaining spring extended along the rear side of the bar and a connection between said spring and the head, said connection being pivoted on and movable with the head to bring the line of tension of said spring alternately at opposite sides of the axis of the head to retain the head in either of two positions.

6. The combination with a type bar, of a type head mounted thereon and having angularly stop faces and a guide, said stop faces coacting with the bar to limit the movement of the head, a link pivoted to the head and extended through the guide, a spring connected to the link and a trigger extended from said link, the connection between the link and head being movable to present the line of tension at opposite sides of the axis of the head.

In testimony whereof I hereunto affix my signature.

HARRY A. FOOTHORAP.
